UNITED STATES PATENT OFFICE.

ERNEST F. RASSMAN, OF CHARLOTTESVILLE, VIRGINIA.

CAN-WASHING MACHINERY.

1,211,878.

Specification of Letters Patent. Patented Jan. 9, 1917.

Application filed September 30, 1916. Serial No. 123,054.

To all whom it may concern:

Be it known that I, ERNEST F. RASSMAN, a citizen of the United States, and resident of Charlottesville, in the county of Albemarle, and in the State of Virginia, have invented a certain new and useful Improvement 5 in Can-Washing Machinery, and do hereby declare that the following is a full, clear, and exact description thereof.

10 My invention relates to can washing machinery, and more particularly has to do with the operation of sterilizing-cleansing of milk can tops, and generally stated the object of my invention has been to produce 15 an apparatus which will be as automatic in its operation as is possible, so that a minimum of manual effort, time and labor will be required, which shall be extremely simple, so as to avoid heavy first cost in 20 constructing it and repairs, and which withal can be depended upon to efficiently do the work required, and with this object in view my invention consists in the apparatus constructed substantially as hereinafter specified and claimed.

25 In the accompanying drawings—Figure 1 is a side elevation thereof; Fig. 2 is an end elevation.

Briefly described, the apparatus shown in 30 the drawings comprises a track along which the can tops placed on edge roll, a series of steam nozzles, or jets being situated alongside the path down which the can tops roll, and valve mechanism which is automatically 35 opened and held open by the action of the can tops as they roll past the series of nozzles, or jets. The workman simply places the can tops, one after another, in the track and they then require no further handling 40 until they have left the track.

The track consists preferably of an angle iron 10 with its two webs, or flanges diverging upward so as to form lateral supports for both sides of the edge of the can tops 45 resting thereon, and above said angle irons there are two parallel bars, or rails 11 between which the upper portion of the can top is situated, and it is thereby maintained in the upright position necessary to its rolling along the track. Said track and said 50 guide rods are supported in an inclined position by a framework 12 consisting of uprights, or posts and horizontal members. The track has intermediate its ends a vertically 55 movable section 13 which at its lower

most end is connected by a pivot, or hinge 14, so that said section is capable of up and down movement, and at its higher end it is pivotally connected to a vertical rod 15 upon which is a coiled spring 16 that at its upper 60 end bears against a collar 17 on the rod, and at its lower end against a plate 170 on the frame work, which spring normally acts to hold the movable section in alinement with the stationary sections at each end thereof. 65 The spring has such tension that it yields under the weight of a can top upon the movable section. A lug 18 on the higher end of the hinge section on the underside arrests the upward movement of said section when 70 it is in such alinement. Downward movement of the section is limited by providing a preferably vertically adjustable collar 19 on a vertical supporting post 20 for the lower end of the upper, or higher stationary 75 section of the track, which stop collar is adapted to be engaged by a projection from the spring-engaging collar 17.

Adjacent the side of the can tops as they roll along the hinged section of the track, is 80 a pipe 21 having in its side toward the can a series of holes 22 which form jets, or nozzles, and said jet pipe is connected by a pipe 23 with a source of supply of steam. The pipe 23 has a valve 24 for controlling the flow of 85 steam to the jet nozzles, and the handle 25 of said valve is connected to the rod 15 so that upon the depression of the rod by the downward movement of the hinged section 90 of the track the valve will be opened and 95 kept open as long as the can top remains on said movable section, so that throughout the the time of its travel along, the latter it receives the steam jets, and is subjected to the desirable sterilizing treatment. When there 95 are no can tops on the movable section, the spring 16 acts to lift the rod 15, and close the valve.

As the use of my apparatus involves 100 merely placing the can tops on the edge of the track whereupon under the action of gravity they can move down the track and automatically cause the turning on and off of the steam, the manual labor involved is but little, the work is done with great rapidity 105 and it is done thoroughly because of the length, or extent of the series of jets past which the can tops travel.

The operation of the apparatus shown 110 and described, has, I believe, been sufficiently

set forth and it will be evident that such apparatus attains the object of my invention as hereinbefore set forth.

While I prefer, as an excellent embodiment of my invention, apparatus having the construction and organization of elements as illustrated in the drawings, it is to be understood variations from that construction within the scope of the appended claims 10 may be made without departing from the spirit of my invention.

The various parts of the apparatus are not shown in the drawings in strict proportion, or relative arrangement, as departures exist 15 in these particulars for the sake of clearness of illustration.

Having thus described my invention what I claim is—

1. In a machine of the class described, the 20 combination of a track along which the can part is adapted to move, a section of said track being movable into and out of alinement with the remainder, a pipe having an outlet adjacent said movable section, a valve in said pipe, and a connection between said valve and said movable section for transmitting movement from the latter to the valve to operate it.

2. In a machine of the class described, the 30 combination of an inclined track along which the can part is adapted to move, a section of said track being movable into and out of alinement with the remainder, a pipe having an outlet adjacent said movable

section, a valve in said pipe, and a connection between said valve and said movable section for transmitting movement from the latter to the valve to operate it. 35

3. In a machine of the class described, the combination of a track having upwardly extending separated guide flanges, a pair of guide rails spaced apart above said track along which the can part is adapted to move, a section of said track being movable into and out of alinement with the remainder, a pipe having an outlet adjacent said movable section, a valve in said pipe, and a connection between said valve and said movable section for transmitting movement from the latter to the valve to operate it. 40 45

4. In a machine of the class described, the combination of a track having upwardly extending separated guide flanges, a pair of guide rails spaced apart above said track along which the can part is adapted to move, said track having a jointed section upon which said section is adapted to swing, a pipe having a series of nozzles extending alongside of the swinging section of the track, a valve in said pipe, a rod connecting 55 said section and the valve to operate the latter, and a spring acting normally to move said swinging section into alinement with the remainder of the track.

In testimony that I claim the foregoing 60 I have hereunto set my hand.

ERNEST F. RASSMAN.
